Des. 232,167
Patented July 23, 1974

232,167

BOAT STORAGE COMPARTMENT LID OR THE LIKE

Carl R. Cordell, Jr., 215 Idlewood Drive,
Hot Springs, Ark.

Filed Dec. 8, 1972, Ser. No. 313,406

Term of patent 14 years

U.S. Cl. D12—70   Int. Cl. D12—99

FIG. 1.

FIG. 2.

FIG. 3.

FIG. 1 is a perspective view showing the top, one end, and one side of a boat storage compartment lid or the like according to my invention;

FIG. 2 is an end view thereof at an enlarged scale; and

FIG. 3 is a perspective view taken from the bottom thereof.

I claim:

The ornamental design for a boat storage compartment lid or the like, as shown and described.
